UNITED STATES PATENT OFFICE

2,607,056

APPARATUS FOR FORCE LASTING SHOES

Allan Shaw Pringle, Galt, Ontario, Canada, assignor to United Shoe Machinery Corporation, Flemington, N. J., a corporation of New Jersey

Application December 17, 1949, Serial No. 133,560

3 Claims. (Cl. 12—15)

1

This invention relates to apparatus for shaping the heel end portions of shoes upon their lasts and is herein illustrated as embodied in apparatus for effecting relative heightwise movement of the heel end portion of a shoe and a last mounted therein thereby to perform a force lasting or slip lasting operation upon the shoe. The invention is illustrated in the drawing as incorporated in apparatus designed primarily for operation on shoes of the type illustrated in United States Letters Patent No. 2,385,743, granted September 25, 1945, on an application filed in the name of Samuel B. Vaisey. It is to be understood, however, that the invention is not limited in its scope to apparatus constructed and arranged to operate on shoes of the type illustrated in the Vaisey patent but is applicable to apparatus for performing a force lasting or slip lasting operation on any and all shoes having closed heel ends.

It is an object of the present invention to provide apparatus for effecting relative heightwise movement of the heel end portion of a shoe and a last mounted therein. More specifically it is the object of the invention to effect such relative heightwise movement of a shoe and a last mounted therein in order to force the last heightwise thereof into intimate contact with the interior or foot facing surface of the shoe bottom.

With the above objects in view the present invention in one aspect thereof comprises apparatus consisting of a standard having a gripper jaw mounted thereon and constructed and arranged to engage the top margin of a shoe and to grip it against the outer surface of the standard and hold it during the shoe-shaping operation. For closing the gripper jaw on the shoe a plunger is mounted in a guideway extending from top to bottom of the standard, said plunger having mounted thereon means operable to effect the closing of the gripper jaw on the shoe. For imparting a shaping operation to the shoe there is mounted in the upper portion of the guideway a slide having mounted thereon a member constructed and arranged to engage the cone portion of a last mounted in the shoe. The slide is moved upwardly by the plunger to effect the shoe-shaping operation, the operation of the slide being timed to commence after the plunger has operated to bring the gripper jaw into gripping engagement with the upper.

The invention will now be illustrated with reference to the accompanying drawing which discloses in sectional elevation apparatus embodying the features of the present invention.

2

The drawing illustrates a manually operated bench-mounted device for forcing a last upwardly into the heel portion of a shoe to bring the sole face of the last into intimate contact with the foot-facing surface of the shoe bottom thereby to impart to the shoe its final shape. In the drawing the illustrated apparatus is shown as operating on a shoe of the type disclosed in the Vaisey patent above referred to, the back line 10 portion of the shoe being extended to provide a tab by which the shoe is gripped and held while the last is forced upwardly against the interior of the shoe bottom.

In the drawing the numeral 2 identifies a standard the base 3 of which is secured to a bench 4 by screws 6. The standard has a central vertical bore 8 in the upper portion of which is mounted a sliding shaft 10 and in the lower portion of which is mounted a plunger 12. The shaft 10 is provided with a flange 14 which is normally held by gravity against the top of the standard 2. The upper surface of the flange 14 serves as a support for a last such, for example, as the last 16 illustrated in the drawing. The flange 14 engages the cone face of the last and the tapering upper end portion 18 of the sliding shaft 10 extends upwardly into the thimble 20 in the rear portion of the last. In order to prevent the sliding shaft 10 from being inadvertently moved upwardly out of the standard, the shaft is provided with a longitudinal slot 22 and a pin 24 is mounted in the standard and arranged to extend through said slot.

For holding the rear end portion of the shoe 35 against upward movement, a gripper jaw 26 is pivotally mounted on a cross pin 28 mounted in ears formed in the standard 2, one of said ears being identified by the numeral 30. The work engaging face 32 of the gripper jaw is corrugated as is also the portion 34 of the standard adjacent to the gripper jaw. The rear portion of the illustrated shoe 36 is extended vertically to provide a tab 38 which is positioned between the gripper jaw 26 and the corrugated surface of the standard, as shown in the drawing.

For actuating the shaft 10 and the gripper jaw 26 in predetermined time relation to each other a treadle 40 is pivotally mounted between upwardly extending ears of a bracket 42 secured to the floor beneath the bench 4. A connecting means, such, for example, as the illustrated flexible wire cable 44 is connected to the treadle 46 pivotally mounted between the ears of a bracket 48 fixed to the base 3 of the standard 2 and extending downwardly therefrom into an

opening 48 formed in the bench 4. The flexible wire cable 44 extends over the pulley 46 and down to a collar 50 secured to the lower end portion of the plunger 12 which extends downwardly through the opening 48 and for a short distance below the bench 4. The flexible wire cable 44 is connected to a pin 52 mounted in the collar 50 and suitably arranged with relation to the pulley 46. For imparting counterclockwise or closing movement to the gripper jaw 26 a bracket 54 secured to the plunger 12 by headed screws 56 carries a plunger 58 constructed and arranged to engage the bottom surface of the gripper jaw. The illustrated plunger is mounted in a bore 60 formed in an offset upward extension 62 of the bracket 54. The bore 60 communicates with a counterbore 64 which extends downwardly to the lower extremity of the extension 62 and mounts the head 66 of the plunger 58. The head 66 is axially bored to receive a spring 68 the lower end of which is mounted on a stud projecting upwardly from a threaded plug 70 mounted in the internally threaded lower end portion of the extension 62. The gripper jaw 26 is normally held in its open position illustrated in the drawing by a spring 72 seated in a bore formed in an extension 74 of the gripper jaw and arranged to bear against the top surface of an outward extension 76 of the standard. In order to provide clearance for the operation of the plunger 58, the extension 76 has formed therein an open end slot 78. In order to provide clearance for the vertical movement of the bracket 54 the standard 2 has a slot 80 formed therein and arranged to communicate with the bore 8.

When the gripper jaw 26 is in its retracted position the bracket 54 rests against the bottom end face of the slot 80 and is held against upward movement by a spring 82 surrounding the lower portion of the plunger 12 and confined between the base of the standard 2 and the collar 50 mounted on said plunger. The bracket 54 is formed with parallel side faces which have sliding engagement with the vertical walls of the slot 80 formed in the standard and thus maintain the width-wise position of the plunger 58 and the orientation of the collar 50. In order to permit the gripper jaw 26 to close and grip the work before upward movement is imparted to the sliding shaft 10, the plunger 12 is so constructed and arranged that in its rest position, as shown in the drawing, the upper end face of the plunger is spaced from the lower end face of the shaft 10 to an extent commensurate with the upward movement of the plunger 12 required to close the gripper jaw.

In the operation of the illustrated apparatus a last, such as the last 16 illustrated in the drawing, is inserted into the shoe 36 and the shoe on its last is arranged in an inverted position and mounted on a tapering upward extension 18 of the sliding shaft 10. In mounting the last on the extension 18 it is so orientated that the tab 38 at the rear portion of the shoe is positioned between the gripper jaw 26 and the corrugated face 34 of the standard 2. After so positioning the shoe, the treadle is depressed to close the gripper jaw 26 on the work and to impart upward movement to the sliding shaft 10 in predetermined time relation thereby to force the

last upwardly and bring its bottom face into intimate contact with the foot-facing surface of the shoe bottom.

Having thus described my invention what I claim as new and desire to secure by Letters Patent of the United States is:

1. Apparatus comprising a standard having a guideway extending from top to bottom thereof, a gripper jaw mounted on the standard and constructed and arranged to engage the top margin of a shoe and grip it against the outer surface of the standard, a slide mounted in the upper portion of the guideway in the standard, a member carried by the slide and constructed and arranged to engage the cone portion of a last mounted in the shoe, a plunger slidably mounted in the lower portion of the guideway in the standard, means carried by the plunger and operable by upward movement of the plunger to close the gripper jaw on the top margin of the shoe, and means for effecting upward movement of the plunger first to close the gripper jaw on the shoe and thereafter to impart upward movement to the slide thereby to force the last into intimate contact with the interior of the shoe bottom.

2. Apparatus comprising a standard having a bore extending from top to bottom thereof, a gripper jaw pivotally mounted on the standard and constructed and arranged to engage the top margin of a shoe and grip it against the outer surface of the standard, a shaft slidably mounted in the upper portion of the bore in the standard, a member carried by the shaft and constructed and arranged to engage the cone portion of a last mounted in the shoe, a plunger slidably mounted in the lower portion of the bore in the standard, a bracket fixed to the plunger, a spring pressed pin mounted in the bracket and constructed and arranged to close the gripper jaw on the shoe during upward movement of the plunger, and an actuator for moving the plunger upwardly first to close the gripper jaw on the shoe and thereafter to impart upward movement to the sliding shaft thereby to force the last into intimate contact with the interior of the shoe bottom.

3. Apparatus comprising a standard, a sliding shaft in the standard for lifting a last in a shoe, a gripper jaw mounted on the standard and arranged to grip the upper of a shoe against the standard, a slide initially spaced from the shaft, and means on the slide for engaging the gripper and forcing it yieldingly against the upper during initial movement of the slide, further movement of the slide lifting the shaft to force the last into the shoe the upper of which is held by the gripper.
